ALUMINUM SPRINGBOARD

Jack M. Ulanovsky, Los Angeles, Calif., assignor
to Paddock Pool Equipment Co., Los Angeles,
Calif., a corporation of California

Application February 10, 1951, Serial No. 210,351

8 Claims. (Cl. 272—66)

1

This invention relates to diving boards, and more particularly to a diving board constructed principally of metal. While the word "board" usually connotes a wood material, it is used herein in the broader sense of a structural article of any material of little thickness and of a length substantially exceeding its width. It may be one integral piece of material, as is often the case in wooden diving boards, or may be built up from several pieces of the same or different materials in a manner found suitable for constructing metal diving boards. A diving board is then an article of a length substantially exceeding its width and of a relatively small thickness, mounted or to be mounted at the side of and projecting over a swimming and diving pool or other body of water suitable for swimming and diving, to be used as a springboard by a diver to give him an upward and outward movement from the board before falling downward into the water.

The proportions of a properly designed diving board are such as to provide, when conventionally mounted, the required deflection of the tip of the board under a given load which in turn generates a corresponding upward force sufficient for diving. Moreover, the board must be so designed that the combination of forces acting upon it in normal usage shall not anywhere produce stresses in excess of the endurance limit of the material. A board so designed has long life under conditions of continued stress reversals.

It is apparent that a metal board has certain advantages over a wooden board:

1. A metal board may be standardized with uniform diving characteristics—an important factor in competitive diving.

2. By proper choice of material and proper design, a metal board may be of relatively light weight and, nevertheless, have a safety factor far in excess of that of a wooden board of similar weight. Longer usefulness of the board is thereby assured, and may be safely guaranteed by the manufacturer.

3. By the use of suitable metal alloys, the destructive action of fungi and the weather may be greatly reduced.

This inventor has as his object the production of a metal diving board of relatively light weight, required deflection, high flexure strength, durability, and high torsional stability. The importance of the latter quality will appear in the course of the description of the invention. In designing a metal diving board for greater strength and durability, it was found possible to produce one several times stronger than a wooden

2

board, with a "throw" better than that of the existing boards, and with a torsional stability greater than that of any diving board now in existence.

In line with the terminology of structural elements, the diving board of the invention may be termed a beam. To attain the quality of light weight, as well as to realize more fully the above mentioned objects of the invention, a unique compound beam made of several single beam shapes is provided by the invention. The dimensional ratios of the single beam shapes and the dimensional ratios of the assembled compound beam will vary somewhat with the metal or metals used, the dimensional ratios in the case of each metal being determined in accordance with good engineering practice. There are present, however, certain characteristics of the beam shapes, and certain relative arrangements of the component beam shapes in the compound shape, which are common to diving beams constructed in accordance with the invention, irrespective of the metal used. The subject matter of the invention is so defined in the appended claims.

23 In the drawings,

Figure 1 is a side elevation of a diving board of the invention mounted with its outer end projecting over the edge of a swimming pool;

Figure 2 is a plan view of the board and its mount shown in Figure 1;

Figure 3 is an elevational view of the diving board;

Figure 4 is a section along line 4—4 of Figure 3;

Figure 5 is a section along line 5—5 of Figure 3; and

Figures 6 and 7 are sectional views similar respectively to Figures 4 and 5, but of a diving board embodying the invention in a modified form.

Referring to Figures 1 and 2, a diving board, generally indicated by the numeral 11 is secured at 12, as by through bolts 20, to a cross pipe 13, supported by two pipe standards 14 fixedly embedded at their lower ends in a concrete foundation slab 15, at a suitable distance from the rim 16 of a swimming pool 17. At a fulcrum point 18 the board 11 rests loosely upon a horizontal cross pipe 19, which is supported at each end by a pipe structure in the form of an inverted U, comprising a longitudinally arranged horizontal pipe 21, and two vertical pipes 22, which are fixedly embedded at their lower ends in the concrete slab 15. Preferably the cross pipes 13 and 19 are at such relative levels that the board

11 slopes gradually upwardly toward its outer end, in accordance with standard diving board practices.

The diving board, as may be seen in Figures 4 and 5, is a compound beam made up of four separate beams, i. e., an upper, downwardly opening channel section 23, a lower, upwardly opening channel section 24, and two solid rectangular section bars 25. Preferably, these separate beams are made of aluminum, or an aluminum alloy, although under some circumstances stainless steel or other metals may be indicated as a suitable selection of material.

To illustrate a diving board of properly engineered dimensions, and with no implied limitation of the scope of the invention, we will assume that the diving board is made of aluminum, is 16 feet long, and 20 inches wide. Then, for satisfactory performance, the following dimensions will be approximately correct. The channel section 23 will be of $\frac{1}{16}$ inch sheet aluminum. Its web 26 will be 20 inches wide, and its flanges 27 will be $2\frac{1}{8}$ inches wide for the inner 6 $\frac{1}{2}$ feet of the length of the board to a point designated 28 on the drawing. From that point the flanges will taper uniformly to a width of 1 $\frac{1}{2}$ inches at the outer end of the board.

The channel section 24 is also of $\frac{1}{16}$ inch sheet aluminum, has a web 29 and two flanges 30, which are each spaced about 3 inches inwardly from the adjacent flange 27 of the upper channel section. The sheet metal of the lower channel section extends laterally beyond the upper edge of its flanges 30, the sheet metal being bent outwardly at each side of the diving board to form a horizontal web 31 which lies against the underside of the web 26 of the upper channel section, and being then bent downwardly to form a flange 32. This flange 32 lies parallel to the flange 27 of the upper channel section, is spaced therefrom about $\frac{1}{8}$ of an inch, and its lower edge is level with the lower edge of the flange 27 from end to end of the diving board.

The stiffening bars 25 occupy the space between the flanges. The upper edges of the bars are spaced about $\frac{1}{2}$ inch below the underface of the web 26. The lower edges are flush with the lower edges of the flanges 27 and 32, conforming to the taper of these flanges. The flanges 27, and 32, and the bar 25 are secured together at each side of the diving board by aluminum rivets 34.

The web 29 of the lower channel section is bowed upwardly in cross section with an elevation or crown of about $\frac{3}{4}$ inch. This arching of the web prevents longitudinal buckling of the web when the web is subjected to longitudinally acting compressive stresses as the outer end of the board is flexed downwardly. The entire diving board is provided with the necessary flexure strength and stiffened against localized buckling and failure by the lower web 29, the flanges 30, 27, and 32, and the bars 25. Twisting of the board brought about by the diver standing or jumping in a position to apply more of his weight to one side of the board than the other, is prevented by the lateral stiffening effect of the two webs which cross connect these six flanges and two bars. The construction may be considered as providing two cantilever beams one at each side of the diving board and tied together by the upper and lower webs, so that vertical movements of one beam cause similar simultaneous vertical movements of the other beam. This resistance to torsional stress is of great advantage

to the diver, and especially when he dives into the water at either side of the board.

Figures 6 and 7 illustrate a modified form of the invention in which only the lower channel 5 differs from the form it has in Figures 4 and 5. This channel 24a has a central upwardly bowed web 29a, and two flanges 35, the upper edges of which abut the lower surface of the web 26a. The flanges 35 are spaced from the flanges 27a 10 as in Figures 4 and 5, and the stiffening bar 25a fills the space between the flanges and is secured to the flanges by rivets 34a.

The shape of the channel section 24a permits its being made with a taper toward the outer end 15 of the diving board, and this taper is evident from a comparison of the spacing between the webs 29a and 26a in the two Figures 6 and 7.

End plates 36 and 37 at the inner and outer ends of the board respectively, serve to give the 20 board a neat appearance, to close the openings between the webs against entrance of foreign objects and to protect the feet, legs and bodies of the divers from injurious contact with the otherwise exposed, jagged ends of the channel sections.

The upper surface of web 26 is usually faced 25 for at least the outer end portion of the diving board with a fastened-down covering (not shown) of a flexible, non-slip material such as coco-matting.

I claim:

1. A flexible resilient metal diving board, comprising the combination of: a sheet metal top plate of downwardly facing channel cross-section, including a longitudinally extending web and downturned flanges along the longitudinal edges thereof, said web edges defining the entire width of the upper surface of said diving board, and a sheet metal bottom plate of upwardly facing channel cross-section, including a longitudinally extending web positioned in spaced relation below said web of said top plate, and flange formations along the longitudinal edges thereof secured to said downturned flanges of said top plate, all so constructed and arranged as to form a hollow rectangular-like box section stiffened by said spaced webs against longitudinal buckling, and stiffened by the lower web against torsional stress.

2. A flexible resilient metal diving board, comprising the combination of: a sheet metal top plate of downwardly facing channel cross-section, including a longitudinally extending web and downturned flanges along the longitudinal edges thereof said web edges defining the entire width of the upper surface of said diving board, and a sheet metal bottom plate of upwardly facing channel cross-section, including a longitudinally extending web positioned in spaced relation below said web of said top plate, and flange formations along the longitudinal edges thereof secured to said downturned flanges of said top plate, said web of said bottom plate having a transverse arch formation extending longitudinally along the length of the bottom plate, all so constructed and arranged as to form a hollow rectangular like box section stiffened by said spaced webs against longitudinal buckling, and stiffened by the lower web against torsional stress.

3. A flexible resilient metal diving board, comprising the combination of: a sheet metal top plate of downwardly facing channel cross-section, including a longitudinally extending web and downturned flanges along the longitudinal

edges thereof said web edges defining the entire width of the upper surface of said diving board, longitudinal metal stiffening bars adjacent the inside surfaces of said downturned flanges, and a sheet metal bottom plate of upwardly facing channel cross-section, including a longitudinally extending web positioned in spaced relation below said web of said top plate, and flange formations along the longitudinal edges thereof including flange portions abutting the inside surfaces of said stiffening bars, and means securely fastening said flanges on said top plate, said stiffening bars, and said flange portions of said bottom plate in rigid assembly with one another.

4. The subject matter of claim 3, wherein said webs of said top and bottom plates are substantially parallel longitudinally of the board, but wherein said flanges of said top plate, said stiffening bars, and said flange portions of the lower plate taper outwardly of the board for at least a substantial outer portion of the length of the board.

5. A flexible resilient metal diving board, comprising the combination of: a sheet metal top plate of downwardly facing channel cross-section, including a longitudinally extending web and downturned flanges along the longitudinal edges thereof, longitudinal metal stiffening bars adjacent the inside surfaces of said downturned flanges, and a sheet metal bottom plate of upwardly facing channel cross-section, including a longitudinally extending web positioned in spaced relation below said web of said top plate, and flange formations along the longitudinal edges thereof, including portions turned upwardly from the longitudinal edges of said web of said bottom plate, outward portions extending from said upwardly turned portions and abutting the under surface of the web of said top plate, and downwardly turned portions extending from the outwardly turned portions, said downwardly turned portions abutting the inside surfaces of said stiffening bars, and means securely fastening said flanges on said top plate, said stiffening bars, and said downwardly turned portions of said flange formations of the bottom plate, all in rigid assembly with one another.

6. A flexible resilient metal diving board, comprising the combination of: a sheet metal top plate of downwardly facing channel cross-section, including a longitudinally extending web and downturned flanges along the longitudinal edges thereof, longitudinal metal stiffening bars adjacent the inside surfaces of said downturned flanges, and a sheet metal bottom plate of up-

wardly facing channel cross-section, including a longitudinally extending web of arched cross-section positioned in spaced relation below said web of said top plate, and flange formations along the longitudinal edges thereof, including portions turned upwardly from the longitudinal edges of said web of said bottom plate, outward portions extending from said upwardly turned portions and abutting the under surface of the web of said top plate, and downwardly turned portions extending from the outwardly turned portions, said downwardly turned portions abutting the inside surfaces of said stiffening bars, and means securely fastening said flanges on said top plate, said stiffening bars, and said downwardly turned portions of said flange formations of the bottom plate, all in rigid assembly with one another.

7. The subject matter of claim 6, wherein said flanges of said top plate, said stiffening bars, and only the said downwardly turned flange portions of said bottom plate, are tapered outwardly of the board for at least a substantial outer portion of the length of the board.

8. A flexible resilient metal diving board, comprising the combination of: a sheet metal top plate of downwardly facing channel cross-section, including a longitudinally extending web and downturned flanges along the longitudinal edges thereof said web edges defining the entire width of the upper surface of said diving board, longitudinal metal stiffening bars adjacent the inside surfaces of said downturned flanges, and a sheet metal bottom plate of upwardly facing channel cross-section, including a longitudinally extending web positioned in spaced relation below said web of said top plate, and upwardly turned flanges along the longitudinal edges of said bottom plate abutting the inside surfaces of said stiffening bars, and means securely fastening said flanges on said top plate, said stiffening bars, and said flanges on said bottom plate in rigid assembly with one another.
